[57] ABSTRACT

A writing pad holder such as a binder or folder for sheets of paper or the like comprising a base panel including a cover forming a folder therewith to hold the sheets of paper, a visual owner's identification plate pivoted onto said base panel about an upright and a transverse axis relative thereto to adjust the horizontal and vertical directions of the owner's identification plate, a printing plate secured on one side of the latter to print owner's identification onto the paper, an ink pad slidable over the printing plate and a window into the cover to register with the visual owner's identification when the cover is closed.

FIG. 7

WRITING PAD HOLDER WITH IDENTIFICATION AND PRINT MEANS

This invention relates to a writing pad holder, such as a folder or binder for sheets of paper, drawings, or the like.

In the present schooling system, it is rather difficult for a teacher, professor or lecturer to remember the names of all the numerous students he is teaching to. This most often results in a substantial psychological barrier against effective communication with the students due to their resentment to any impersonalized manner of being called. In group discussions, such as in seminars, it is also a problem to ensure that the participants get acquainted and readily identify each other.

It is a general object of the invention to provide a writing pad holder, such as a folder or binder for sheets of paper or the like, with an identification device adapted to provide a visual identification of the owner of the corresponding holder to a nearby person.

It is a more specific object of the invention to provide a writing pad holder with an identification device which is arranged to selectively display the owner's identification in one of a plurality of horizontal and/or vertical directions such as to be particularly viewed when looked at from that direction.

It is another object of the invention to provide a writing pad holder which includes a visual identification device which is also constructed to print the owner's identification on the paper carried by the holder.

It is a further object of the invention to provide a writing pad holder which includes a visual identification plate and a cover having a window for pivoting of the identification plate between an erected position when the cover is open into operative position and a flat position to display visual identification when the cover is closed.

The invention will now be described in detail with reference to a preferred embodiment thereof which is illustrated, by way of example, in the accompanying drawings, in which:

FIG. 1 is a perspective view of a writing pad holder according to the invention shown in closed position;

FIG. 2 is a plan view of the same writing pad holder shown in open position;

FIG. 3 is a perspective view of a portion of the writing pad holder particularly illustrating the identification elements thereof;

FIG. 4 is a cross-sectional view as seen along line 4-4 in FIG. 5;

FIG. 5 is a partial plan view of the writing pad holder particularly showing the identification plate in flat position;

FIG. 6 is a plan view of the whole identification plate assembly according to the invention;

FIG. 7 is a side view illustrating the printing by the identification plate;

FIG. 8 is an elevation view illustrating the insertion of an inking pad forming part of the present invention; and

FIG. 9 is a cross-sectional view as seen along line 9-9 in FIG. 8.

The illustrated writing pad holder includes a base panel 1, a cover panel 2 and an edge panel 3 which are integrally formed into a folder. A three-ring binder mechanism 4 is secured against the inner side of the

edge panel 3 in any suitable manner to carry loose leaves onto the base panel in position for writing thereon. A clip 5 is secured to the base panel 1 and is arranged to hold fast or retain the sheets of paper into the writing position.

A base plate 6 is held flat against the inner face of the base panel 1 by screws 7 engaged into the slots 8 and such as to allow transverse sliding of the base plate relative to the adjacent edge of the base panel. A stopper 9 is secured to the base panel 1 to engage the inner edge of the base plate 6 and limits the inward displacement thereof.

A cup-shaped support 10 is rotatably mounted onto the base plate 6 and is integrally formed of a bottom portion 11, a tubular portion 12 and a stub pivot 13. The latter projects downwardly from the bottom portion 11 and is pivotally secured to the base plate to define an elevation axis for the pivoting of the whole support 10. A carrier or piston 14 is inserted into the cup-shaped support 10 for lengthwise displacement into the latter. A radial groove 15 extends into the upper or outer face of the piston member 14. A slot 16 extends through the tubular portion 12 and lengthwise of the latter. A spline or internal ridge 17 is integrally formed with the tubular portion 12 and extends lengthwise thereof in engagement into a corresponding notch in the periphery of the piston or carrier 14. A spring 18 is mounted into the cup-shaped support 10 and arranged to bias the latter outwardly.

An identification plate 19 is pivotally carried by the piston 14 and includes a supporting post 20 having its free lower end pivoted into the groove 15 by a transverse pivot 21. As may be seen, the supporting post 20 pivots into a plane passing through the groove 15 and the slot 16 and preferably perpendicular to the base panel 1 and base plate 6. On the outer face of the identification plate 1, there is mounted a nameplate or separate indicia 22 forming the name of the owner of the writing pad holder.

On the inner face of the identification plate 19, there are secured suitable rubber strips 23 forming a rubber stamp bearing all the necessary and desired information to fully identify the owner, such as the name, grade, year and school of a student. An ink pad including a metal cover 24 and a felt 25 are formed with lateral flanges 26 arranged to slidably engage complementary flanges along the opposite sides of the rubber stamp strips.

A window 27 is formed through the cover portion 2 and arranged to register with the nameplate on the outer face of the identification plate 19 when the latter is folded into flat or substantially horizontal position and the cover is closed, as shown in FIG. 1. Preferably, the window 27 includes a transparent plastic sheet 28 secured to the cover 2.

Sheets of paper 29 are inserted into the folder, binder or holder and held fast by the three rings and the clip 5. When, for instance, the student using it is in the classroom, he opens the writing pad holder and pivots the identification plate 19 about the transverse pivot 21 to the erected position in which the indicia 22 or nameplate is outwardly displayed to be seen by the teacher at the front of the class, as best shown in FIG. 3. If, for instance, the teacher is not directly in front of the student, the latter may rotate the identification plate 19 at an angle about the afore-mentioned elevation axis in the direction of the teacher.

The student may identify each page of his notes or work by pulling out the cover formed by the ink pad, pivoting the identification plate about the transverse axis and pressing down in the direction of the arrow 30 in FIG. 7. Before closing the holder, the ink pad is slid into place to cover the rubber stamp and thereby prevent smearing the uppermost sheet of the pad. It must be noted that the slot 16 allows the rubber stamp to always rest flat onto the uppermost sheet no matter how many sheets remain into the pad.

If the user of the writing pad holder does not have to take notes but wants to nevertheless display his identification, he pulls out the base plate 6 such that the cup-shaped support 10 and the identification plate 19 stand outside the corresponding edge of the base panel 1 and cover portion 3. The latter may then be closed while the identification stands erected into its display position.

Obviously, many changes in the details of the invention may be made without departing from the spirit and scope of the invention as defined in the appended claims. For instance, the particular construction of the pivoting support, the identification plate and the paper retaining means may be changed without changing their desired function.

The term writing pad holder is used as a generic term into the disclosure and the claims and is meant to mean any type of device adapted to hold one or more sheets of paper, map, drawings or the like in flat position for writing thereon. It may, for instance, include a single panel without a cover.

I claim:

1. A writing pad holder comprising a base panel adapted to carry sheets of paper in position for writing thereon, a support mounted onto said base panel adjacent one edge thereof outwardly of said sheets of paper and including a carrier member slidably displaceable toward and away from said base panel for adjustment to the thickness of said sheets of paper on the latter, an identification plate hinged to said carrier member about a transverse axis, hinged about an elevation axis relative to said base panel, and arranged for displacement with said carrier member towards and away from said panel, a visual identification against one face of said identification plate and a printing plate against the opposite face of said identification plate, and the latter being arranged to pivot relative to said base panel between an erected position outwardly displaying said visual identification and inwardly folded position defined by flat engagement of said printing face against the uppermost one of said sheets of paper.

2. A writing pad holder as defined in claim 1, further including a base plate slidably mounted onto said base panel and arranged for outward projection from one edge of the latter and said support is pivoted onto said base plate and arranged for outward projection from said one edge.

3. A writing pad holder as defined in claim 1, further including a cover having an ink pad therein and constructed and arranged to slide over said opposite face for covering and inking said printing plate.

4. A writing pad holder as defined in claim 1, wherein said support includes a tubular member rotatably mounted relative to said base panel about said elevation axis and arranged coaxially with the latter, said

carrier member forms a piston axially displaceable into said tubular support member, and a spring engages said piston member and is arranged to outwardly bias the latter away from said base panel.

5. A writing pad holder as defined in claim 4, wherein said tubular member is cup-shaped and integrally forms a bottom portion, a tubular portion and a stub pivot projecting outwardly from said bottom portion, said identification plate includes a supporting post portion 10 and an identification plate portion, said piston member has a radial groove on the outer face thereof, said post portion has a free end pivoted into said groove about said transverse axis and into a plane passing through said groove, and said tubular portion has a slot extending lengthwise thereof and into said plane for pivotal passage of said post portion towards and away from said flat position of the identification plate.

6. A writing pad holder as defined in claim 1, wherein said base panel includes a cover portion forming a folder therewith to hold and carry said sheets of paper, and said cover portion has a window therethrough arranged to register with said visual identification when said cover portion is folded into closed position and said identification plate is in said inwardly flat position.

7. A writing pad holder as defined in claim 6, further including a sheet retaining means secured to said base panel and constructed and arranged to hold said sheets of paper in said writing position and adjacent said support within each of said printing plate for said printing thereon.

8. A writing pad holder as defined in claim 7, wherein said sheet retaining means includes a three-hole binder mechanism and a clip operatively secured to said base panel and arranged to hold fast said sheets for proper printing thereon.

9. A writing pad holder as defined in claim 8, further including a base plate slidably mounted onto said base panel and arranged for outward projection from one edge of the latter, a cover having an ink pad therein, said support being pivoted into said base plate and arranged for outward projection from said one edge, said cover being arranged to slide over said opposite faces for covering and inking said printing plate, said support including a tubular member rotatably mounted relative to said base panel about said elevation axis and arranged coaxially with the latter, said carrier member forming a piston axially displaceable into said tubular support member, a spring engaging said piston member and arranged to outwardly bias the latter away from said base panel, said tubular member being cup shaped and integrally forming a bottom portion, a tubular portion and a stub pivot projecting outwardly from said

- 55 bottom portion, said identification plate including a supporting post portion and an identification plate portion, said piston member having a radial groove on the outer face thereof, said post portion having a free end pivoted into said groove about said transverse axis and into a plane passing through said groove, and said tubular portion having a slot extending lengthwise thereof and into said plane for pivotal passage of said post portion towards and away from said flat position of the identification plate.
